MECHANICAL DANCING FIGURE

Filed Sept. 14, 1921

2 Sheets-Sheet 2

UNITED STATES PATENT OFFICE.

FRANK WATSON, OF LYNN, MASSACHUSETTS.

MECHANICAL DANCING FIGURE.

Application filed September 14, 1921. Serial No. 500,533.

To all whom it may concern:

Be it known that I, FRANK WATSON, a citizen of the United States, residing at Lynn, in the county of Essex and Commonwealth of Massachusetts, have invented certain new and useful Improvements in Mechanical Dancing Figures, of which the following is such a full, clear, and exact description as will enable others versed in the art to which it appertains to make and use the same.

My invention relates to mechanical dancing figures and more particularly to the type designed for use upon phonographs or other motor driven instruments, and has for its purposes:

1. To produce a dancing figure which will roll, tap, shuffle, and beat the stage in a manner natural to life, and conforming to standard musical rhythms.

2. To provide an improved dancing figure self-contained and always ready for use without alteration or adjustment.

3. To provide an improved combination base and rotating timing piece.

4. To provide an improved adjustable tripod mounting.

5. To provide an improved flexible and vibrating supporting means for the dancing figure.

6. To provide an improved auxiliary dancing figure and self contained equipment adaptable for use on cabinet phonographs without screws or other disfiguring attachments.

I accomplish the purposes of my invention as illustrated in the accompanying drawing, in which Figure 1, shows a side view of my device assembled.

Figure 2, shows a front view of my device. Figure 3, shows a top view of my oscillating stage. Figure 4 shows a top view of my base. Figure 5 shows my device placed for use upon an ordinary cabinet phonograph.

Similar characters of reference refer to similar parts throughout the several views.

Referring again to Figure 1, A shows the supporting base. B shows the mounting block which supports the oscillating stage, C, over the end of which at C' is suspended the dancing figure, D. The arms, E, are hinged at the shoulders, E', so as to be free for swinging as the body assumes varying dancing positions. The legs of the figure,

F, are also hinged at the hips, F', and at the knees, F'', so as to likewise allow the legs to freely assume varying positions.

The base, A, at its free end is provided with a round hole through which extends a shaft, G', of the timing cam, G. G², G³, and G⁴, are projections extending upward from the body of the cam, G, which projections as the cam rotates contact with the timing vibrator, H, secured to the underside of the loose end of the stage at a point over which is positioned the dancing figure. As the timing cam rotates, the stage is automatically raised and lowered by the projections, G², G³, and G⁴, acting alternately on the vibrator, H. It will be seen that as each projection, G², G³, and G⁴, respectively approaches and passes under the timing vibrator, H, a rhythmic up and down movement is given to the stage, J, the time being governed by the rotating speed of the cam, G.

The figure proper is supported, from its shoulders, on a wire standard, I, which passes down and through an orifice, J, in the stage, C, to a prepared receiving cavity, K, in the base board, A. The cavity, K, is formed to receive the L shaped terminal, L, of the supporting wire I. The supporting wire is held upright in position within the cavity by the securing button, M, which merely operates to hold the supporting wire at its end, thus allowing free action of the wire in that portion, K', of the cavity, K, which lies parallel to the face of the base board, A. This freedom of the supporting wire, I, in the cavity, K, allows sufficient play for the wire, to result in a natural up and down motion of the body of the dancing figure. As the stage strikes the bottom of its feet, the limbs and body proper are afforded natural and rhythmic motions known to human dancing and heretofore so much desired in dancing figures.

It will be noted that while the mechanism, by means of which the stage is raised and lowered, makes the rise of the stage gradual, its descent is sudden and precipitous. The gradual rise gives to the dancing figure a gliding movement, while the precipitous drop gives a special vim and activity to the dancer, causing it to roll, tap, shuffle and beat the stage in a manner natural to life and conforming to standard musical rhythm.

The vacuum cups under the two outer

supports, combined with the stage upon which the figure dances, create a "drum head" effect, whereby the sound taps of the dancing feet are much intensified and more 5 clearly articulated, this producing added attractiveness of clog dancing.

My device may conveniently be used in connection with a disc phonograph, or any similar device having a motor shaft over 10 which snugly fits the orifice, N, extending through the timing cam, G, so as to give a rotating movement to the timing cam as the motor shaft revolves. Beneath the mounting block, B, are two supporting studs, O 15 and O', on the ends of which are pliable vacuum cups, P and P', which when positioned on a smooth or finished surface securely hold the base of my device and prevent rotation of the same. The cups, P 20 and P', are movable on the studs, O and O', so as to shorten or lengthen the supports to conform to varying heights on different machines.

Having thus described my invention I 25 claim as new and desire to secure by Letters Patent of the United States of America—

1. A device of the character described comprising a supporting base including an oscillatable platform or dancing stage, a 30 jointed dancing figure, means for vibrating the stage for contact with the said figure and suspension means supporting the figure over the said stage and permitting flexible up and down movement of the figure, said means including a flexible figure-supporting wire 35 having a lower L-shaped terminal engaged in a cavity in the said base and a securing button pivoted to the base for engagement over the said terminal to hold the wire in 40 position.

2. A device of the character described comprising a base member, an oscillating platform or stage mounted thereon, a jointed dancing figure, means carried by the base 45 member and supporting the figure in suspension over the said stage to permit flexible up and down movement of the figure when the stage is vibrated, means operable to vibrate the said stage so that the latter is caused to have a gradually upward movement and a precipitous descent imparting a gliding movement and a vim to the dancer, causing it to roll, tap, shuffle and beat upon the stage in a manner natural to life and 50 conforming to standard musical rhythm, and supporting means carried by the said base member for stabilizing the device when in operation and including vacuum cups 55 creating a drum-head effect magnifying and

intensifying the sound beats of the dancing 60 figure upon the stage.

3. A device of the character described comprising a base member, an oscillating stage supported thereon, a jointed dancing figure suspended over the said stage to be actuated by the vibration of the stage into intermittent contact therewith, a rotatable cam member journaled in the base member at one end thereof and presenting an orifice to accommodate a driving element, said cam 70 member having projections extending from the body thereof, a vibrator secured to the under side of the stage above the cam extensions and presenting a depending portion to be successively engaged by the said extensions as the cam rotates for actuating the stage to intermittently contact with the said jointed figure, and means for anchoring the said base member at its other end. 75

4. A mechanical dancing figure comprising a vibratory dancing stage, a jointed dancing figure suspended over the stage, a vertically depending vibrator secured to the underside of the said stage, and a horizontally rotatable cam positioned below the stage and presenting a series of vertical projections disposed to contact alternately with the said depending vibrator during rotation of the cam, said vibrator and the said projections being provided with co-acting cam 90 faces operating to vibrate the stage with a gradual upward movement and a precipitous descent of the latter. 95

5. A mechanical dancing figure, for use in connection with a disc phonograph or any similar machine having a motor shaft, comprising a supporting base, a vibratory dancing stage mounted thereon, a jointed dancing figure suspended over the said stage, means for vibrating the stage into intermittent contact with the said figure including a cam journaled in the said supporting base for engagement over the motor shaft to be rotated thereby, and anchoring means carried by the said base consisting of supporting studs and vacuum cups movable on the studs to raise or lower the base to conform to varying heights on different machines, said cups serving to create a drum-head effect modifying and intensifying the sound beats 100 of the dancing figure upon the said stage. 110

In testimony whereof I affix my signature in the presence of two witnesses.

FRANK WATSON.
